UNITED STATES PATENT OFFICE.

FRANK W. MERRICK, OF BOSTON, MASSACHUSETTS, ASSIGNOR TO AMERICAN STAY COMPANY, OF BOSTON, MASSACHUSETTS, A CORPORATION OF MASSACHUSETTS.

VAMP-STAY FOR SHOES.

1,088,665.

Specification of Letters Patent. Patented Feb. 24, 1914.

Application filed July 10, 1905. Serial No. 268,929.

To all whom it may concern:

Be it known that I, FRANK W. MERRICK, a citizen of the United States, residing at Boston, in the county of Suffolk, State of Massachusetts, have invented a certain new and useful Improvement in Vamp-Stays for Shoes, of which the following is a specification, reference being had therein to the accompanying drawings.

10 Prior to the present invention the vamp-stays in general use for the purpose of preventing the vamp of a shoe from tearing or giving way under strain and wear at the lower end of the front opening of the shoe have been formed of a piece of material doubled and folded upon itself to form a hard and finished folded edge to show above the upper edge of the vamp with which it is used, the said edge being molded into convex shape so that in use only a short segment thereof projects into sight. The described character of the stay necessitates a folding operation in the course of its manufacture. The folded stay has a tendency to open or unfold after being manufactured, rendering it necessary to close or fold the same at the time of applying it to the vamp, and also rendering it necessary for the operator to pay special attention to retaining it 20 in folded condition while it is being stitched in place. The folding of the material of which the stay is composed doubles the thickness of the stay, and, even in those instances in which the folded-over portion has been reduced in size so as to render it smaller than the larger body-portion upon which it lies, the increase in thickness resulting from superimposing one layer of the stay upon another makes the presence of the stay underneath the vamp of a shoe plainly discernible in consequence of the upward bulge of the vamp, the contour of the stay being visibly outlined on the front of the finished shoe. In making application of a stay of 30 one of the kinds heretofore in use there has been a tendency to deflection of the stay when the needle of the sewing machine by which the stitching is being done arrives at and strikes the first edge of the stay in making the seam. So also there is a tendency for the presser-foot to catch against the prominence at the edge of the stay, and as a result thereof to deflect the stay. In molding the folded edge of the stay into convex shape, as aforesaid, the free marginal por-

tion of the folded over portion or flap is left more or less full. Consequently, after the stitching this portion is capable of stretching more or less upon the application of strain to opposite portions of the vamp, 60 with the result that such strain is allowed to come upon the stitches, causing the latter to break.

The objects of the invention are to provide a vamp-stay having a finished reinforced and beaded edge capable of being produced without a folding operation; to obviate the folding operation and the tendency of the stay thereby produced to unfold; to provide a vamp-stay which will not 70 produce an elevation or bunch of the vamp under which it is employed, and the presence of which beneath the vamp will not be discernible; to obviate the tendency of the stay to become deflected by the needle or 75 presser-foot of the sewing machine by which it is secured in place; and to provide a vamp-stay of flat and substantially uniform character having no fullness to extend and allow strain to come on stitches and break 80 the latter.

The invention consists in a vamp-stay for shoes, having a thin body or apron of single unitary thickness without break in uniformity through the length thereof, and which underlies a vamp without causing unevenness of the latter, and also having a solid unfolded raised bead which lies outside and close against the exposed edge of 90 the vamp.

The invention consists, further, in a vamp-stay for shoes, having a thin body or apron of single unitary thickness without break in uniformity through the length thereof, with the opposite two ends thereof, and preferably the lower edge thereof, gradually tapered in thickness, the said body adapted to underlie a vamp without causing unevenness of the latter, the vamp-stay also having a solid unfolded raised bead which lies outside and close against the exposed edge of 95 the vamp.

The invention is illustrated in the drawings, in which latter,—

Figure 1 shows in elevation a vamp-stay 105 embodying the invention. Fig. 2 is a top edge view thereof. Fig. 3 is a view showing the same in transverse section. Fig. 4 shows portion of a shoe with a vamp-stay embodying the invention in place therein. 110

Having reference to the drawings,—the vamp-stay is designated 1. It is formed of suitable material, leather being the material best adapted for the purpose. It is composed of a single thickness of unfolded material, as indicated by the sectional view, Fig. 3. Along one edge it is formed with a solid raised, *i. e.*, unfolded bead 3, which projects at one surface of the stay. The 10 said bead gives a finish and at the same time reinforces the stay. The opposite portion 4, and the two lateral portions or ends 5, 5, are gradually reduced or tapered in thickness to their edges. Preferably this gradual 15 reduction or taper is secured by skiving the said portions to their edges.

A vamp-stay embodying the invention cannot change its form or shape prior to being secured in a shoe, as in consequence of 20 opening out or unfolding, as in the case of a vamp-stay consisting of material which is folded upon itself. No special difficulty is experienced in holding and securing the same in place during the operation of assembling the parts of the upper and forming the vamp-seam 14, Fig. 4, inasmuch as 25 it has no tendency to be deflected in the manner previously explained. The raised solid bead lies unobtrusively alongside the free 30 edge 15 of leather, while the tapering or skiving of the portions 4, 5, 5, obviates the production of ridges or bunches in the leather beneath which the stay is concealed.

I claim as my invention:—

1. A vamp-stay for shoes, having a thin 35 body or apron of single unitary thickness without break in uniformity through the length thereof, and which underlies a vamp without causing unevenness of the latter, and a solid unfolded raised bead which lies outside and close against the exposed edge of the vamp. 40

2. A vamp-stay for shoes, having the thin body or apron of single unitary thickness without break in uniformity through the 45 length thereof, with the opposite two ends thereof gradually tapered in thickness, and which underlies a vamp without causing unevenness of the latter, and a solid unfolded raised bead which lies outside and close 50 against the exposed edge of the vamp.

3. A vamp-stay for shoes, having the thin body or apron of single unitary thickness without break in uniformity through the 55 length thereof, with the opposite two ends thereof and its lower edge tapered to thin edges, and which underlies a vamp without causing unevenness of the latter, and a solid unfolded raised bead which lies outside and close against the exposed edge of the vamp. 60

In testimony whereof I affix my signature in presence of two witnesses.

FRANK W. MERRICK.
